UNITED STATES PATENT OFFICE.

FREDERIC E. WEBB, OF BOSTON, MASSACHUSETTS.

REVERSIBLE SIGN FOR HORSE-CARS.

SPECIFICATION forming part of Letters Patent No. 449,506, dated March 31, 1891.

Application filed December 9, 1890. Serial No. 374,104. (No model.)

To all whom it may concern:

Be it known that I, FREDERIC E. WEBB, a citizen of the United States, and a resident of Boston, in the county of Suffolk and State of Massachusetts, have invented new and useful Improvements in Reversible Signs for Horse-Cars, of which the following, taken in connection with the accompanying drawings, is a specification.

Figure 1 represents a plan view showing my improved reversible signs arranged on top of a horse-car. Fig. 2 represents an enlarged central longitudinal section on the line X X shown in Fig. 1. Fig. 3 represents a perspective view of one of the reversible signs; and Fig. 4 represents a cross-section on the line Y Y shown in Fig. 2.

Similar letters refer to similar parts wherever they occur on the different parts of the drawings.

A represents the top or roof of a horse-car or other vehicle or conveyance, and B represents one of the improved reversible signs, which is preferably made four-sided, as shown in Figs. 1, 2, and 3, and mounted on a shaft or spindle b, which is loosely journaled in one end in a bracket or bearing b', that is suitably secured to the car-top A, as shown in Figs. 1 and 2. To the opposite end of the spindle b is secured the handle or hand-wheel b'', as shown in Figs. 1 and 2. The end of the spindle b near the hand-wheel b'' is made square in section, as shown at b³ in Figs. 1 and 2, and is adapted to rest in a corresponding recess B' in the post or bracket B'', that is secured in a suitable manner to the car-top, as shown in Figs. 1, 2, and 4.

The bracket B'' has in its upper end an enlarged perforation B³, communicating with the recess B', by which arrangement the handle end of the spindle b may be raised up into the enlarged perforation B³ to allow the said spindle to be turned around its axis whenever it is desired to change or reverse the sign B, and after the latter has been so changed or reversed it is locked in position by placing the square end b³ of the spindle b in the locking-recess B' in the bracket B'', as shown in Figs. 2 and 4.

For the purpose of enabling the conductor or person in charge of the sign to adjust it without going outside of the car to see if the

right sign is displayed, I provide one or both ends of the sign B with indicators or letterings b⁴ b⁴ b⁴ b⁴, corresponding to the wording of the respective sides of said sign, as shown in Fig. 3. I also provide the sign with means for turning or reversing it from the inside of the car or from below the roof A, which is done by means of a shaft or spindle b⁵, journaled in a bearing b⁶, secured to the roof A, said spindle passing loosely through a perforation in said roof, and has attached to its lower end a handle or hand-wheel b⁷, as shown in Fig. 2. To the upper end of said spindle b⁵ is secured a small bevel-gear b⁸, the teeth of which mesh into the teeth of a similar bevel-gear b⁹, secured to the sign-spindle b, as shown in Figs. 1 and 2. Thus, if the operator desires to change or reverse the sign from the inside of the car, he takes hold of the hand-wheel b⁷ and pushes it upward sufficient to cause the square spindle end b³ to come into the enlarged perforation B³, when by turning said hand-wheel b⁷ a rotary motion is imparted to the sign B by means of the gear connection above mentioned.

C represents a similar reversible sign on the opposite side of the car, and c represents the shaft or spindle to which it is secured, said spindle being loosely journaled in the bearings c' c' secured to the car-roof.

D and E represent similar reversible signs arranged, respectively, at opposite ends of the car-roof, as shown in Fig. 1.

d and e are the spindles for the said respective signs D and E, and d' d' e' e' are the bearings in which said spindles d and e are journaled.

For the purpose of enabling the operator to adjust all of said signs at one operation, I gear the spindles of said signs together, as shown in Fig. 1, where b¹⁰ represents a bevel-gear meshing in the teeth of the bevel-gear d'', secured to the spindle d. d³ is a similar bevel-gear secured to the opposite end of said spindle d, the teeth of which mesh in the teeth of the bevel-gear c'', secured to the spindle c. c³ is a similar bevel-gear secured to the opposite end of the spindle c, the teeth of which mesh in the teeth of the bevel-gear e'', secured to the spindle e, as shown in Fig. 1. Thus it will be seen that all the signs may be reversed or adjusted and locked in position simply by

manipulating the hand-wheel b'' on the spindle b , or the hand-wheel b^7 , as above mentioned.

The invention, although particularly designed and adapted for horse-cars, may, however, to equal advantage be used for other purposes where a reversible sign or signs are needed.

Having thus fully described the nature, construction, and operation of my invention,

10 I wish to secure by Letters Patent, and claim—

15 1. The reversible sign B , secured to the shaft b , said shaft being loosely journaled in one end in the bearing b' , and having its other end b^8 made square and vertically adjustable, combined with the bracket B'' , having the recess B' for receiving the square portion of the said spindle, and the enlarged perforation B^3 , into which the spindle is raised while being turned for adjusting or reversing the sign, substantially as and for the purpose set forth.

20 2. The reversible sign B and its spindle b , secured together, said spindle being loosely journaled in one end in the bearing b' , and having its other end square and adapted to be locked and vertically adjustable in the bracket B'' , having the recess B' and enlarged perforation B^3 , as described, in combination with the gear b^9 , secured to the spindle b , and the gear b^8 , meshing in the former and secured to the spindle b^5 , said spindle being journaled in the bearing b^6 , capable of longi-

tudinal adjustment therein and provided with a hand-wheel or handle b^7 , substantially as and for the purpose set forth.

25 3. The reversible sign B and its spindle b , secured together, said spindle being loosely journaled in one end in the bearing b' , and adapted to be vertically adjustable in its other end in the bracket B'' , in combination with indicators b^4 b^4 at the end of the sign 40 corresponding to the lettering of the faces of said sign, substantially as and for the purpose set forth.

4. The reversible sign B and its spindle b , secured together, said spindle being loosely 45 journaled in one end in the bearing b' , and adapted to be vertically adjustable in its other end in the perforated recessed bracket $B' B'' B^3$, in combination with one or more reversible signs $C D E$, having spindles journaled in bearings, said spindles being all positively geared together, substantially as and for the purpose set forth.

In testimony whereof I have signed my name to this specification, in the presence of 55 two subscribing witnesses, on this 5th day of December, A. D. 1888.

FREDERIC E. WEBB.
